[57] CLAIM

The ornamental design for a lavatory, as shown and described.

DESCRIPTION

FIG. 1 is a left, top, front perspective view of a lavatory embodying my new design;

FIG. 2 is a top plan view thereof;

FIG. 3 is a front elevational view thereof, the rear, right side, and left side elevational views being identical to the front elevational view shown;

FIG. 4 is a bottom plan view thereof; and,

FIG. 5 is a cross-sectional view thereof taken along line 5—5 of FIG. 2.

The dotted line representations of a mounting environment in FIG. 1, and of holes in FIG. 4, are for the purpose of illustration only, and form no part of the claimed design.
